UNITED STATES PATENT OFFICE.

HARRY S. C. WALKER, OF ALEXANDRIA, PENNSYLVANIA.

BRICK-MACHINE.

1,022,165.

Specification of Letters Patent.

Patented Apr. 2, 1912.

Application filed August 25, 1910. Serial No. 578,855.

To all whom it may concern:

Be it known that I, HARRY S. C. WALKER, a citizen of the United States, residing at Alexandria, in the county of Huntingdon and State of Pennsylvania, have invented 5 certain new and useful Improvements in Brick-Machines, of which the following is a specification.

My invention relates to improvements in 10 brick making machines, and more particularly to machines for making silica brick, the primary object of the invention being to provide improvements of this character which will dispense with the necessity for 15 the hands touching the stock during the entire operation of forming the brick.

A further object is to provide an improved table over which the molds are moved between adjustable guide rails, and 20 during such passage are subjected to the action of a press, a slicker, and an ejector.

A further object is to provide an improved press under the complete control of the operator for pressing the stock into the 25 molds.

A further object is to provide an improved mechanism which I term a slicker, which serves to smooth the stock in the molds.

30 A further object is to provide an improved ejector for forcing the brick out of the mold.

A further object is to provide an improved car or carrier adapted to move the 35 molds along the table from one operation to the next, and so on.

A further object is to provide an improved arrangement of levers, gearing, and 40 power transmission for controlling the operation of the several mechanisms.

With these and other objects in view, the invention consists in certain novel features of construction and combinations and arrangements of parts, as will be more fully 45 hereinafter described and pointed out in the claims.

In the accompanying drawings: Figure 1, is a view in front elevation illustrating my improvements. Fig. 2, is an end view illustrating the brick press. Fig. 3, is a perspective view of one of the molds. Fig. 4, is a fragmentary enlarged elevation of the end of 50 the apparatus illustrating the press. Fig.

5, is a plan view of Fig. 4. Fig. 6, is a fragmentary view in front elevation illustrating my improved slicker. Fig. 7, is a plan view of Fig. 6. Fig. 8, is a view in section on the line 8—8 of Fig. 7. Fig. 9, is a view in section on the line 9—9 of Fig. 7. Fig. 10, is a fragmentary view in front elevation illustrating the ejector mechanism. Fig. 11, is a plan view of Fig. 10. Fig. 12, is a view in section on the line 12—12 of Fig. 11. Fig. 13, is a view in section on the line 13—13 of Fig. 11. Fig. 14, is a fragmentary plan view illustrating the gearing and drum for driving the carrier or car. Fig. 15, is an enlarged fragmentary view in elevation illustrating the gearing controlling the operation of the ejector, and Fig. 16, is a fragmentary sectional view illustrating the ejector proper.

1, represents a table or platform which may be constructed in various ways, is hollow and on its upper plate or surface two 75 guide rails 2, 2, are positioned, are located parallel to each other and serve as guides for brick molds 3, one of which is illustrated in Fig. 3. These rails 2, 2, are adjustably held by set screws 4, which project 80 through threaded openings in lugs 5 at the sides of the table, and by means of these screws the rails 2 may be positioned the desired distance apart so as to accommodate any ordinary size of mold.

85 While I refer to part 3 as a brick mold, it is to be understood that the same comprises a plurality of brick molds which are open at top and bottom, the top of table 1 serving as a bottom for the molds while 90 the bricks are being formed.

At the right hand end of the table 1, referring particularly to Figs. 1, 2, 4, and 5, is located my improved press which will 95 now be described in detail.

A frame 6 is secured on the table, and is connected at the top by a cross rod 7 on which a lever or walking beam 8 is pivotally supported between its ends. This lever or walking beam comprises an open framework, and at its forward end is provided with pins 9 which project into slots 10 in the upper ends of standards 11, the lower ends of said standards secured to a heavy block or bar 12, which serves as a presser to crush the 105 stock into the molds. These standards 11

project through openings in a cross bar 13 on frame 6, so as to guide the vertical movement of the presser.

The lever or walking beam 8, at its rear end, is connected by downwardly projecting arms 14, with crank pins 15 on wheels 16, the latter secured to a shaft 17 supported in bearings 18 on table 1. This shaft 17 is driven by a belt 19 which connects a drive 19 pulley 20 on the drive shaft 21, with a pulley 22 on shaft 17. Drive shaft 21 is supported in hangers 23, and is of sufficient length to extend throughout the machine so as to drive all of the several parts. The 15 walking beam or lever 8 is also provided at its rear end with counter-weighted arms 24, which serve to counterbalance the presser block or bar 12.

The belt 19 above referred to is loose, and unless tightened will slip on the pulley 22, and not drive shaft 17, hence the press will be idle. To tighten this belt and start the press, a pulley 25 is provided and is located between the runs of the belt and supported 25 on a forked lever 26, the latter fulcrumed between its ends on brackets 27 secured to table 1. The forward end of this lever 26 is connected by a link 27 with a rod 28, and said rod 28 connects with a hand lever 29 pivotally supported at its lower end in a bracket 30. This lever 29 is located in convenient reach of the operator, so that he may by manipulating this lever, start and stop the press at will.

35 The mold containing the stock is positioned on the table between the rails 2, and located below the bar or block 12, and while in this position, lever 29 is moved so as to tighten the belt 19 and cause the press to reciprocate up and down crushing the stock, and forcing it into all parts of the mold. After the pressing operation is completed, the mold is slid along the table 1 to a point under a smoothing mechanism which I term 45 a slicker, and to facilitate this movement of the mold, I provide a car or carrier 32 which is in the form of a table having uprights or legs 33, said uprights or legs 33 provided with rollers 34 which are located above and below rails 35 supported on the platform 31 above referred to.

Elevated bars or brackets 31 are provided to support the rails 35 above referred to. 55 On top of the carrier 32 a swinging frame 36 is pivotally mounted on a pin 37, and is adapted to swing horizontally so that the frame 36 may lie longitudinally of the carrier or at right angles thereto, and when at right angles to the carrier, will project 60 across the table and in the path of the mold, and the frame may be locked in this position by means of a pin 38 which is adapted to be positioned in an opening 39 in the carrier.

65 When the frame is so locked with rela-

tion to the carrier, a movement of the carrier on its rails will cause the frame to engage the mold which projects slightly above rails 2, and move the mold longitudinally of the table from one position to another, as for example, from the press to the slicker, and from the slicker to the ejector, the means for moving said carrier being hereinafter described in connection with the ejector.

The part which smooths the brick, and which I refer to as the slicker, is located approximately midway the ends of the table 1, and is supported upon a frame 40. This frame 40 provides a rotary mounting for two parallel screw-threaded rods 41. On one end of each of these rods 41, gears 42 are secured, and between said gears 42 and in mesh therewith, a third gear 43 is located and secured upon a short shaft 44 supported in frame 40. These gears 42, and 43, are of the same diameter and are turned by means of a belt 45 which connects a drive pulley 46 on drive shaft 21 with a pulley 47 on one of the rods 41. A cross bar 48 is provided at its ends with blocks 49 having semi-circular screw-threaded faces engaging the screw-threads of rods 41. These blocks 49 are adjustably connected with the cross bar 48 by means of set screws 50, and the said cross bar is connected by a hanger 51 with a block 52 located centrally below the same.

53 represents a car which is mounted on rails 54, and is provided with rollers 55 located above and below the rails, so that the car is prevented from vertical movement. This car 53 is located directly below the block 52 and the bar 51, and is provided centrally with a guide sleeve 56 in which 100 a vertically movable shaft 57 is mounted. This shaft 57 is bored at its ends as shown at 58 to receive and key a shaft 59 which projects through the block 52, and is held against longitudinal movement in the block, 105 hence, these shafts 57, and 59, telescope relatively to each other within certain limits.

On the upper end of shaft 59, a beveled gear 60 is secured and meshes with a beveled gear 61 on a short shaft 62 supported in the 115 hanger 51 and provided with a pulley 63 which is located above but in frictional contact with a longitudinally disposed belt 64, the latter supported upon pulleys 65 mounted in hangers 66 on frame 40. One of these 120 shafts 65 is provided at its end with a beveled gear 67 meshing with a similar gear 68 on the short shaft 44, so that the belt 64 is driven by means of the gears 42 and 43 above described. On the lower end of the 125 shaft 57, a disk 69 is secured by means of a set screw 70. This disk 69 is provided with an eccentric opening to receive a pin 71 projecting upwardly from the center of a flat circular plate 72, which latter is secured to 130

a rectangular plate 73, which constitutes the slicker proper, suitable rollers 74 being provided on the slicker to engage the table 1 and limit the downward pressing action of the slicker.

The upper face of plate 72 is provided with a circular rough or irregular rack 75 on which a wheel or roller 76 is mounted to turn, below, and connected to disk 69, so that as shaft 57 revolves, it will cause the slicker to move in the arc of a circle, and at the same time roller 76 turning on the rack 75 will impart to the slicker a vibrating motion, which will cause the slicker not only to smooth the stock in the mold, but will vibrate and cause the material to pack as it is smoothed.

The car 53 is provided at one side with a depending bar 77 having a platform 78 at its lower end. A hand lever 79 is pivotally connected at one end to the bar 77, and between its ends is connected by a link 80 with a lever 81, the latter fulcrumed between its ends on a block 82, and connected to a grooved collar 83, the latter connected to the shaft 57, so that by movement of the lever 79, this shaft 57 will be moved longitudinally. A short movement of this lever will simply serve to elevate the slicker off the mold, the continued movement will cause shafts 57 and 59 to move vertically and elevate block 52 and bar 48, causing the threaded blocks 49 to lift off of rods 41, and allow the car 53 to move the slicker back to its starting point. The operation of the slicker therefore, is continued throughout a longitudinal movement of the mold on the table, as the screw-threaded rods 41 will cause the car 53 and the slicker and operating mechanism carried thereby to move longitudinally, the operator stopping the operation when he thinks proper by operating the lever 79, and this lever may be locked in a bifurcated standard 84 on platform 78 with the parts in elevated position. After the bricks have been smoothed or slicked they are moved longitudinally of table 1 to the left hand end of the apparatus where my improved ejector mechanism is located. Table 1, at this end of the machine, is provided with a transverse passage-way 85 which is bridged by hinged rail sections 86. These sections 86 constitute continuations of the rails 2, and are hinged for a purpose which will herein-after appear. In the passage 85, and secured to the opposite faces of the table, are transversely located bars 87, which serve as supports for a plate 88 located below the rail section 86, and on which the bricks are to be deposited, the mold 3 being moved longitudinally of the table onto this plate ready for the ejecting operation.

The ejecting mechanism is supported upon a frame 89. Two parallel shafts 90 and 91 are supported at the upper end of

frame 89, and are provided with gears 92 of the same size, but spaced apart and out of mesh, although in alinement. These gears are adapted to be engaged by a gear 93 which is normally out of mesh with either, 70 but is adapted to be moved into mesh with both so as to cause a transmission of motion from the shaft 91 to shaft 92. On the shaft 91, a pulley 94 is located and is connected by a belt 95 with a drive pulley 96 on the 75 drive shaft 21.

The pulley 93 is mounted in the bifurcated end of a lever 97 which is fulcrumed between its ends on a bracket 98 on frame 89, and is connected by a rod 99 with a hand lever 100, the latter supported on a bracket 101 located in convenient reach of the operator. To prevent accidental movement of the gear 92, a spring-pressed pawl 102 is provided and is normally pressed into engagement with the teeth of the gear 92, and this spring-pressed pawl 102 is provided with an operating cord 103 which is located in suitable guide eyes 104 on lever 97 and rod 99, and provided with a hand-hold 105 in convenient reach of the operator, so that he may release the gear when he operates the lever 100 so as to move gear 93 into mesh with the gears 92.

On shaft 90, small pinions 106 are fixed 95 and mesh with vertically disposed rack bars 107 which are guided in openings in cross bars 108 in frame 89, and are provided at their lower ends with mold engaging jaws 109. These jaws 109 are provided at their 100 lower ends with inwardly projecting lips 110 which engage in recesses 111 in the ends of mold 3, and the said jaws are also provided with rollers 112 which are adapted to project into recesses 113 in the 105 ends of the mold, insuring a perfect grip between the jaws and the mold, allowing them to engage without damage to either.

The jaws 109 are connected by links 114 with the rack bars 107, and are normally pressed 110 inwardly into operative position by means of flat springs 115, said springs however allowing the jaws to be moved outward so as to receive the mold between them. An internally screw-threaded vertically disposed sleeve 116 is fixed in the frame 89 and in this sleeve a vertically disposed screw-threaded rod 117 is mounted and provided at its upper end with a hand wheel 118 to turn the same. This rod supports at its 120 lower end, and moves longitudinally, a plate 119 which is provided with a plurality of depending pins 120 having small plates 121 at their lower ends which are of approximately the same dimensions as the upper faces of 125 the bricks in the mold. These plates 121 act as plungers to force the brick out of the mold or rather hold the bricks against vertical movement while the mold is being elevated by means of the rack bars 107. When 130

the plate 88 above referred to is in position, and the mold with the bricks therein is moved onto this plate, the rack bars 107 are permitted to lower by means of the gears 92 and 93 above referred to, and the jaws 109 are placed in engagement with the ends of the mold. The plungers 121 are then lowered until they engage the upper faces of the brick. The gear 93 is then thrown into mesh with the gears 92 and shaft 90 will be turned in a direction to elevate the rack bars 107 which will cause the mold to be elevated while the bricks are being held on the plate 88. As soon as the mold is lifted off the bricks, hand wheel 118 is operated to elevate the plungers so that the plate 88 with the bricks thereon may be removed and carried away, and to facilitate this removal of the bricks the rail sections 86 are hinged 20 as above explained.

To move the carrier 32 longitudinally of the machine, a rope or cable 122 is secured to the carrier and is wound upon a drum 123. This drum 123 is secured upon a shaft 124 on which a gear 125 is fixed. A gear 126 is spaced from gear 125 and is adapted to be connected therewith by means of a gear 127 which is supported in the forward lower end of a vertically movable rod 128. The upper end of this rod 128 is connected to a lever 129 which is fulcrumed between its ends on a bracket 130 on frame 89, and at its other end is connected by a rod 131 with a hand lever 132 supported on a bracket 133 in convenient reach of the operator. Gear 126 is fixed to a shaft 134 having a beveled pinion 135 thereon meshing with a similar pinion 136 on a shaft 137 which is continuously driven by means of a belt 138. This belt 138 connects a pulley 139 on the shaft 124 with a pulley 140 on shaft 91. It will thus be noted that the lever 132 may be operated any time to drop the gear 127 into mesh with gears 125 and 126 thus causing the drum 123 to turn and wind the rope or cable 122 thereon, thereby pulling the carrier from left to left and when this gear 127 is elevated, the carrier may be moved from left right unwinding the rope or cable from drum. On the shaft 124 a pulley 141 is fitted and this pulley may serve to drive a pulley (not shown) for carrying the stock away from the machine.

The operation of my improvements is as follows: The mold containing the stock is put in position under the press and the carrier is operated to crush the stone within the mold. The carrier 32 is then utilized to move the mold from the press to the side, when the slicking or smoothing operation takes place, and then move the mold to the point of discharge where the bricks are ejected from the mold as above explained, it being understood that the three operations are being continuously carried

out, so that with a complete machine of this character, three molds are continuously in use, one being under the presser, another under the slicker, and the third under the ejector, so that the three operations are carried on simultaneously while the molds pass step by step from one operation to the other.

Various slight changes might be made in the general form and arrangement of parts described without departing from my invention, and hence I do not limit myself to the precise details set forth, but consider myself at liberty to make such changes and alterations as fairly fall within the spirit and scope of the appended claims.

Having thus described my invention, what I claim as new and desire to secure by Letters Patent is:

1. In a brick machine, the combination with a table, and a mold guide thereon, of a track over the mold guide, a car on the track, telescoping shafts supported by the car, means for turning the shafts, a disk on the lower shaft having an eccentric bearing, a slicker plate, a slicker secured thereto, a central pin on the slicker plate located in the bearing in the disk, a circular rack on the slicker plate, and a roller on the disk running on the circular rack, substantially as described.

2. In a brick machine, the combination with a table, and a mold guide thereon, of a track over the mold guide, a car on the track, telescoping shafts supported by the car, means for turning the shafts, a disk on the lower shaft having an eccentric bearing, a slicker plate, a slicker secured thereto, a central pin on the slicker plate located in the bearing in the disk, a circular rack on the slicker plate, and a roller on the disk running on the circular rack, and means for moving the car longitudinally as the shafts are turned, substantially as described.

3. In a brick machine, the combination with a table, and a mold guide thereon, of a track over the mold guide, a car on the track, telescoping shafts supported by the car, means for turning the shafts, a disk on the lower shaft having an eccentric bearing, a slicker plate, a slicker secured thereto, a central pin on the slicker plate located in the bearing in the disk, a circular rack on the slicker plate, a roller on the disk running on the circular rack, means for moving the car longitudinally as the shafts are turned, and a lever on the car constructed to elevate the slicker and the shafts and stop the longitudinal movement of the car, substantially as described.

4. In a brick machine, the combination with a table, and a mold guide thereon, of a track over the mold guide, a car on the track, telescoping shafts supported by the car, means for turning the shafts, a disk on the lower shaft having an eccentric bearing,

a slicker plate, a slicker secured thereto, a central pin on the slicker plate located in the bearing in the disk, a circular rack on the slicker plate, a roller on the disk running on the circular rack, parallel screw-threaded rods, means for turning the rods, a cross bar connected with the car, blocks on the cross bar having screw-threaded recesses receiving the rods and moved thereby, and means for elevating the bar and blocks

out of engagement with the screw-threaded rods, substantially as described.

In testimony whereof I have signed my name to this specification in the presence of two subscribing witnesses.

HARRY S. C. WALKER.
